W. A. EVERSON

RAZOR BLADE HOLDER

Filed March 21, 1923

INVENTOR.

W. A. EVERSON

BY
Watson E. Coleman
ATTORNEY.

UNITED STATES PATENT OFFICE.

WILLIAM A. EVERSON, OF MARTINSBURG, WEST VIRGINIA.

RAZOR-BLADE HOLDER.

Application filed March 21, 1923. Serial No. 628,613.

To all whom it may concern:

Be it known that I, WILLIAM A. EVERSON, a citizen of the United States, residing at Martinsburg, in the county of Berkeley and State of West Virginia, have invented certain new and useful Improvements in Razor-Blade Holders, of which the following is a specification, reference being had to the accompanying drawings.

This invention relates to razor blade holders and more particularly to a device of this type for holding a razor blade so that it may be employed as the blade of a knife.

An important object of the invention is to provide improved means for clamping the blade in adjusted position and more particularly to a means for preventing oscillation of the blade while so positioned.

A further object of the invention is to provide a structure of this character whereby the clamping means set forth in my prior applications, Serial Nos. 614,672, 614,673, and 614,674, filed January 24, 1923, razor blade holders, is improved and rendered more efficient and durable.

These and other objects I obtain by the construction of arrangement shown in the accompanying drawings, wherein for the purpose of illustration is shown the preferred embodiments of my invention, and wherein—

Figure 1 is a side elevation of a knife blade embodying my improved blade holding means;

Fig. 2 is an elevation of the opposite side of the knife;

Fig. 3 is a side elevation with the blade extended;

Fig. 4 is a section on the line 4—4 of Fig. 1;

Fig. 5 is a view of the clamping plate;

Fig. 6 is a side elevation of one of the slide plates;

Fig. 7 is a side elevation of a modification of the invention;

Fig. 8 is a sectional view line 8—8 of Figure 7; and

Figs. 9 and 10 are views of the clamping and slide plates employed in this form.

As set forth in those prior applications hereinbefore mentioned, the razor blade holder proper consists of a casing including spaced side walls 10 and 11 connected by edge walls 12 and intermediate which a blade 13 is mounted for sliding move-

ment, this blade being held in position by a clamping plate 14, through which a clamping screw 15 engaged through an opening of the blade and a corresponding opening in the wall of the casing is disposed. By tightening this clamping screw the blade may be held in extended or withdrawn position. In accordance with the present construction, adjacent the end of the casing an edge wall thereof is removed for short distance and a side wall 10 provided with an extension 16, disposed at an angle to the casing proper and having formed therein a longitudinally extending slot 17. The opposite side wall 11 is terminated short of the side wall 10, so as to expose a portion of the inner surface of the side wall 10, for a purpose presently to appear. Extending through the slot 17 is a bolt 18 which is adjusted longitudinally of the slot and which, when disposed adjacent the inner end of the slot, will engage against the edge of a blade B, carried by the casing when the same is extended. By tightening the bolt 18, the opposite edge of the blade may be forced into engagement with the adjacent edge of a wall 12 and the blade rigidly held by the clamping screw 15, bolt 18, and the engagement of the blade with such wall.

In order to provide for ready operation of the bolt 18 and to eliminate all chance of the operator engaging his fingers with the blade in shifting the bolt in the slot 17, I provide the clamping plate 14 of an angular extension 19, overlying and corresponding to the extension 16, the side wall 10, and having a slot 20 corresponding to the slot 17. Upon the outer face of the wall 10 and upon the remote face of the clamping plate 14, as regards the wall 10, I mount side plates 21, each having an opening 22, in which the bolt 18 fits and a slot 23 extending longitudinally of the side plates and through which the clamping bolt 15 of the plate 14 extends.

It will be seen that with the bolt engaged in the plates 21, shifting of the bolt may be accomplished by shifting the plates 21, and it will further be seen that the bolt 22 may be held in an adjusted position, the clamping engagement being provided by the engagement of the clamping bolt 15, with the side plates 23. The inner faces of these side plates are preferably roughened as indicated at 24, so that they will have a

biting engagement with the walls of the casing and with the clamping plate 14. If desired, the bolt 18 may be tightened after the plates 21 have been adjusted but this will not ordinarily be necessary.

In the form shown in Figures 7 to 10 the clamping plate 14^a engages the blade B through pressure exerted thereon by a clamping set screw 25 extending through the wall of the casing 10, remote from the blade B as regards the plate, the end of this set screw abutting the plate and forcing the clamping plate into engagement with the blade. With this form of my invention I provide a single slide plate 21^a, having an opening through which the securing element 18 is disposed. This plate has not formed therein the slot 23 ordinarily provided in the slide plates but is solid and is abutted by the clamping screw 25 and forced into engagement with the clamping plate 14, in turn forcing this clamping plate into engagement with the blade. It will be seen that in each of the forms of the invention the tightening of a single element serves to secure the blade against longitudinal slippage and to maintain against the edge of the blade the element 18, which prevents rotation of the blade.

30. What is claimed, is:

1. In a razor blade holder, a casing including side and edge walls, one side and one edge wall being terminated short of the opposite side and edge walls, a blade maintained between the side walls of the casing and shiftable to extended and withdrawn positions, an extension formed on the longer side wall at the exposed end thereof and at an angle to the casing, said extension being provided with a longitudinally extended slot and a clamping member slidably mounted in said slot and when positioned at the inner end thereof engaging against the blade to force the same in engagement with the opposite side wall of the casing, a plate abutting the blade, and means extending through said plate, blade, and a wall of the casing for clamping the plate against the blade to maintain the same in adjusted position.

2. In a razor blade holder, a casing including side and edge walls, one side and one edge wall being terminated short of the opposite side and edge walls, a blade maintained between the side walls of the casing and shiftable to extended and withdrawn positions, an extension formed on the longer side wall at the exposed end thereof and at an angle to the casing, said extension being provided with a longitudinally extended slot and a clamping member slidably mounted in said slot and when positioned at the inner end thereof engaging against the blade to force the same in engagement with the opposite edge wall of the casing, a plate

abutting the blade, and means extending through said plate, blade, and a wall of the casing for clamping the plate against the blade to maintain the same in adjusted position, said blade having an angular extension 70 overlying the extension of the side wall and having a slot corresponding to the slot of said extension and through which said clamping member extends.

3. In a razor blade holder, a casing including side and edge walls, one side and one edge wall being terminated short of the opposite side and edge walls, a blade maintained between the side walls of the casing and shiftable to extended and withdrawn 80 positions, an extension formed on the longer side wall at the exposed end thereof and at an angle to the casing, said extension being provided with a longitudinally extended slot and a clamping member slidably mounted in 85 said slot and when positioned at the inner end thereof engaging against the blade to force the same in engagement with the opposite side wall of the casing, a plate abutting the blade, means extending through said 90 plate, blade, and a wall of the casing for clamping the plate against the blade to maintain the same in adjusted position, said blade having an angular extension overlying the extension of the side wall and having a 95 slot corresponding to the slot of said extension and through which said clamping member extends, and slide plates slidably abutting the outer face of said side wall and the remote face of the first named plate through 100 which said clamping member is extended, said slide plates having slots receiving the means clamping the first named plate.

4. In a razor blade holder, a casing including side and edge walls, one side and one edge wall being terminated short of the opposite side and edge walls, a blade maintained between the side walls of the casing and shiftable to extended and withdrawn 105 positions, an extension formed on the longer side wall at the exposed end thereof and at an angle to the casing, said extension being provided with a longitudinally extended slot and a clamping member slidably mounted in 110 said slot and when positioned at the inner end thereof engaging against the blade to force the same in engagement with the opposite side wall of the casing, a plate abutting the blade, means extending through said 115 plate, blade, and a wall of the casing for clamping the plate against the blade to maintain the same in adjusted position, said blade having an angular extension overlying the extension of the side wall and having a 120 slot corresponding to the slot of said extension and through which said clamping member extends, and slide plates slidably abutting the outer face of said side wall and the remote face of the first named plate through 125 which said clamping member is extended, 130

said slide plates having slots receiving the means clamping the first named plate, the faces of said slide plates opposing the first named plate and the wall of the casing being roughened.

5. In a razor blade holder, a casing including side and edge walls, a blade maintained between the side walls, an extension formed on one side wall of the casing at the 10 end thereof through which a blade is adapted to be projected and having a slot formed therein, a clamping plate disposed between the blade and one side wall of the casing, means for forcing said plate into engage-

ment with the blade to bind the same against the opposite wall of the casing, and a plate 15 slideable against the first named plate and having a transversely disposed element slideable in the slot of the casing and adapted to abut against the edge of the blade, said securing element forcing the last named plate 20 into engagement with the first named plate to thereby clamp the first named plate against the blade.

In testimony whereof I hereunto affix my 25 signature.

WILLIAM A. EVERSON.
